United States Patent Office

Des. 183,450
Patented Sept. 2, 1958

183,450

GAME BOARD

Frank W. Easter and Roswell D. Weber, Oxnard, Calif.

Application December 14, 1954, Serial No. 33,562

Term of patent 14 years

(Cl. D34—5)

The figure is a plan view of a game board, showing our new design, said game board being of conventional thickness. The dominant features of our design are shown in full lines. The drawing is shaded to indicate color.

We claim:

The ornamental design for a game board, substantially as shown and described.
